UNITED STATES PATENT OFFICE

WARREN H. McLEOD, OF BOULDER, COLORADO

DESIGN FOR A GOLF TEE

Application filed April 15, 1930. Serial No. 35,255. Term of patent 14 years.

To all whom it may concern:

Be it known that I, WARREN H. McLEOD, a citizen of the United States, residing in the city of Boulder, county of Boulder, and State of Colorado, have invented a new, original, and ornamental Design for a Golf Tee, of which the following is a specification, reference being had to the accompanying drawing, forming a part hereof.

I claim:

The ornamental design for a golf tee as shown.

WARREN H. McLEOD.
